POWER DRIVEN AQUAPLANE

Frank G. Rozanski, Perry, N.Y., assignor to
Aqua-Dart, Inc., Perry, N.Y.

Filed Sept. 26, 1963, Ser. No. 76,741

Term of patent 14 years

(Cl. D71—1)

Fig. 1.

Fig. 2.

Fig. 3.

Fig.4.

Fig.5.

Fig.6.

FIG.1 is a perspective view of a power driven aquaplane showing my new design;

FIG. 2 is a top plan view thereof;

FIG. 3 is a bottom plan view thereof;

FIG. 4 is a side elevational view thereof;

FIG. 5 is a front elevational view thereof; and

FIG. 6 is a rear elevational view thereof.

The side not shown is substantially the same in appearance as the side shown in FIG. 4.

I claim:

The ornamental design for a power driven aquaplane, as shown and described.
